UNITED STATES PATENT OFFICE.

LESLIE WILLIAM MOSES, OF BALTIMORE, MARYLAND.

PRESSER-FOOT.

1,105,819.

Specification of Letters Patent.

Patented Aug. 4, 1914.

Application filed January 26, 1914. Serial No. 814,553.

To all whom it may concern:

Be it known that I, LESLIE W. MOSES, a citizen of the United States, residing at Baltimore, in the State of Maryland, have 5 invented certain new and useful Improvements in Presser-Feet, of which the following is a specification.

The purpose of this invention is to provide a presser-foot for holding the crowns of straw hats while they are being cut off to lower the crowns. Owing to the fact that crown portions of straw hats of the kind worn by men and boys are oval circumferentially, while the feed wheel upon which they 15 are placed while being cut is cylindrical, the rigid curved bars generally used as presser feet for holding the crowns in place against the feed wheels at the cutting points are unsatisfactory, because they do not adapt 20 themselves to the changing contour of the hat crown and tend to catch in the straw and tear the hats, and also to deflect the crowns from the cutting lines. In carrying out my 25 invention, I provide a presser foot which bears upon the crown at two points only, one in advance and the other at the rear of the cutting point, so that the hat crowns will always be held firmly against the feed wheel 30 between these two points. The parts of the presser foot which engage the crown are in the form of rollers, which ride easily over any rough or projecting portions of the straw, these rollers being spring pressed toward the feed wheel and having a limited 35 vertical movement so as to be self adjusting upon the crown.

While the presser foot is designed particularly for use in connection with machines for cutting the crowns of straw hats, or other 40 stiff hats, it is also adapted for holding hat crowns and hats on machines used for sewing sweat bands into the hats, for sewing ribbon bands on hats, and for sewing the brims to the crowns, and generally for holding, while cutting or sewing, any article of a 45 rigid character which is circumferentially oval or elliptical.

In the accompanying drawing, which 50 illustrates my invention, Figure 1 is a side elevation of a hat trimming machine embodying my improvements; Fig. 2 is an end elevation of the same; Fig. 3 is a side elevation of the presser foot detached; Fig. 4 is a detail view illustrating a modification in 55 the mounting of the presser foot rollers, adapting them for movement independently

of one another, and of the connecting bar; and, Fig. 5 is a side elevation of a presser foot illustrating its adaptation to a hat sewing machine.

Referring to Figs. 1 to 3, inclusive, of the drawing, 1 indicates the supporting frame of a hat trimming machine, in which is mounted a feed shaft 2 having thereon a driving pulley 3, a gear 4, and a feed roller 5. The gear 4 meshes with a gear 6 on a cutter shaft 7, which is mounted in a vertically movable frame comprising arms 8, hinged to the supporting frame 1, the arrangement being such that when the hinged 70 frame is swung downward until the gears are in mesh, the two shafts will turn in opposite directions when power is applied to the pulley 3. The feed roller preferably has a milled periphery, as shown, and it is 75 provided with an annular groove 5^a, into which the edge of a circular cutter 9, on the shaft 7, extends. The parts thus far described are of the usual construction.

Upon the arm 8, at the front of the machine, is mounted a lever 10, pivoted centrally at 10^a, and to the downwardly turned arm 10^b of this lever is secured the shank 11 of the presser foot *a*. The presser foot comprises a metal bar or strip 12, having at each end studs 13 which project laterally toward the cutter, and upon these studs are mounted rollers 14. The bar 12 is connected pivotally at about its center to the shank 11 by a stud 15, and preferably a slot 16 is formed 90 in the shank concentric with the axis of the stud 15, and a stop-pin 17, on the bar 12, extends into this slot, the slot and pin connection permitting the bar to rock with respect to the shank to a limited extent, to allow the 95 foot to adjust itself to the work, and serving also to prevent the bar from turning freely about its axis when the presser foot is raised out of engagement with the work. A spring 19 applies tension to the lever to hold the 100 presser foot in engagement with the work on the feed roller, and an adjusting screw 18, bearing upon the arm 10^b, is provided for regulating the tension.

In operation, when it is desired to cut 105 the crown of a hat circumferentially, the hinged portion of the cutter frame is raised, lifting the cutter and presser foot away from the feed roller, and the hat, indicated in dotted lines at 20, is passed over the 110 roller, as shown. The hinged frame is then lowered to bring the cutter and presser foot

into engagement with the crown. The rollers 14 on the presser foot are spaced apart and arranged with respect to the cutter so that one roller will press upon the 5 crown in advance of the point where the cutter engages it, and the other roller will bear upon the crown at the rear of the cutting point. Thus, at the cutting point, the crown will be pressed solidly against the 10 feed roller, and when power is applied to the machine, the cutter and feed roller will revolve in opposite directions, and the former will shear off a portion of the hat crown. As the crowns of straw hats, and 15 other stiff hats, as worn by men and boys, have an oval shape circumferentially, it is difficult with the ordinary presser foot to hold the crown firmly at the cutting point, because of the constantly changing curvature 20 of the crown. The presser foot of my invention, however, constantly bears against the crown at two points only, one in advance and one at the rear of the point where the cutter meets the groove in the feed 25 roller, and by reason of these two points of contact and the pivotal mounting of the bar 12, which carries the presser foot rollers, the foot will adjust itself to the changing contour of the crown as the latter revolves, and will hold the crown firmly 30 against the feed roller at the cutting point midway between the presser foot rollers. The tension of the presser foot may be varied, as will be obvious, by adjusting the 35 screw 18.

Instead of mounting the bar 12 pivotally and mounting the rollers upon studs fixed in said bar, as shown in Fig. 3, which, however, is the preferred arrangement, the rollers 40 may be arranged as illustrated in Fig. 4, each roller being mounted in a block 21 adapted to slide in a slot 22, in the bar 12^a and normally pressed downwardly by an independent spring 23. In such case the 45 bar 12^a may be secured rigidly to the shank 11, if desired, and the presser foot rollers will have an independent movement so that they can adjust themselves to the form of the hat crown.

50 The presser foot may also be applied to machines for sewing sweat bands into hats, or for sewing crowns to brims, this being

sufficiently illustrated in Fig. 5, wherein 24 represents a sewing machine needle, 20^a a partial outline of the feeding device for the hat crown, and the presser foot *a'* comprises the bar 12^b, having the rollers 14 in front and at the rear of a needle guide 25, the bar being centrally pivoted at 15^a to the shank 11^a. It will be obvious that the 60 crown will be pressed at two points, one in advance and one in the rear of the needle, and that at the point where the needle operates the crown will be held firmly against the feed plate, (not shown). 65

The rollers on the presser foot will ride easily over any rough points on the crowns of straw hats without catching in or damaging the material, and without interfering with the cutting or stitching operations. 70

What I claim is:

1. In a machine for operating upon hat crowns, the combination with a curved feeding device adapted to receive a hat crown and a member co-operating with said device for operating upon the crown, of a presser foot for holding the crown against said device at the operating point comprising a shank; a centrally pivoted bar on said shank, two rollers on the bar at opposite 80 sides of its pivotal point, said rollers projecting below the intermediate portion of the bar and adapted to engage the work in advance of and at the rear of the operating point, and resilient means for pressing said 85 rollers toward the work.

2. The combination with a cylindrical feed roller adapted to receive a hat crown and a cutter having its cutting edge meeting the feed roller for severing the crown, 90 of a presser foot comprising a bar having rollers at its ends, said rollers projecting below the intermediate portion of the bar and adapted to simultaneously engage the work in advance of and at the rear of the 95 cutting point, and resilient means for holding said rollers in engagement with the work.

In testimony whereof I have affixed my signature, in presence of two witnesses.

LESLIE WILLIAM MOSES.
